UNITED STATES PATENT OFFICE.

ISIDOR J. KUSEL, OF CHICAGO, ILLINOIS.

SMALL-COIN BANK.

1,392,689.

Specification of Letters Patent.

Patented Oct. 4, 1921.

Application filed January 20, 1919. Serial No. 271,956.

To all whom it may concern:

Be it known that I, Isidor J. KUSEL, a citizen of the United States, residing at Chicago, in the county of Cook and State of Illinois, have invented a certain new and useful Improvement in Small-Coin Banks, of which the following is a full, clear, concise, and exact description, reference being had to the accompanying drawings, forming a part of this specification.

My invention relates to small coin banks.

The principal object of the invention is to provide a very simple and inexpensive construction of bank of this kind.

Another object is to provide a bank which may receive a predetermined number of coins and may not be opened until it receives that number of coins.

Another object of the invention is to provide for the simple and easy opening of the bank when it contains the predetermined number of coins.

Another object of the invention is to make it difficult or impossible to withdraw a coin after its insertion into the bank has been started.

In the accompanying drawings Figure 1 is a side elevation of a coin bank embodying my present invention;

Fig. 2 is a vertical section of the same on an enlarged scale;

Fig. 3 is a longitudinal section taken on line 3-3 in Fig. 2;

Fig. 4 is a horizontal section taken on line 4-4 in Fig. 2;

Fig. 5 is a view of one of the parts of which the bank is made;

Fig. 6 is an elevation of a modified form of device;

Fig. 7 is a longitudinal section of the same; and

Fig. 8 is a vertical section taken on line 8-8 in Fig. 7.

Referring to the drawings I show in Figs. 1 to 4, inclusive, a bank consisting of a shell or casing preferably of cylindrical form, as shown in Fig. 2. This shell or casing preferably consists of an upper member 1 and a lower member 2, which members are preferably made of metal. Upper member 1 has a top 3 and the lower member 2 has a bottom 4. The members 1 and 2 are fitted closely together, as for example by telescoping the lower member into the upper member, so

that normally the two members are held firmly together, but it is possible to separate them and thereby open the bank.

In the construction shown in the figures referred to the lower member 2 is provided with an interior shell or casing 5, which is fixedly secured to the main lower member 2. This member 5 forms the inner part of the lower member, and its upper end portion 5a telescopes into the upper member 1.

As an arrangement for temporarily holding these members 1 and 2 together the upper or outer member 1 is provided with an annular groove or recess 6 conveniently formed by punching out a portion of the material of said member 1. The inner member 5a is provided with one or more beads 7 which will fit into the groove 6 when the two parts of the bank are snapped together, whereby the bead or beads 7 will hold the two members 1 and 2 in engagement and thereby retain the bank normally locked.

The top 3 is provided with a device by which the coins may be acted upon. This is conveniently in the form of a screw 9 threaded into the top 3 and provided with a thumb piece 10 by which it may be turned. Thus the coins may be filled into the bank until they occupy substantially the entire space therein up to the coin slot 11, which is provided in the upper member 1. When this occurs the screw 9 is screwed down into the bank so that its lower end engages the uppermost coin and acts upon it. Further turning of the thumb piece 10 causes the separable member 1 to rise, inasmuch as it is not possible to compress the coins further, it being possible to separate the members 1 and 2. Thus these members 1 and 2 are forced apart by a sufficient operation of the screw 9 and when they are separated the bank is opened and the coins removed.

The bank is preferably of such size as to take a predetermined denomination of coin and a certain number of same. For example, the bank shown in Fig. 1 is of a size to take twenty-five one cent pieces which is sufficient for a United States Government thrift stamp, and thus the bank becomes a thrift savings bank. When these twenty-five one cent pieces are in place, the screw 9 may be operated to open the bank, but until the bank is so filled it cannot be opened, inasmuch as the screw 9 will not

reach the coins and the members 1 and 2 are held together too firmly to be separated by the fingers.

As a matter of further improvement I provide a coin engaging member, preferably in the form of a spring clip 12, which is secured by rivets 13—13 to the inner lower member 5. The upper end 12^a of this clip projects into the coin slot 11 and thereby engages the coins when they are inserted in that slot. The yielding nature of the clip 12 permits the coins to be pushed into the bank but if effort is made to withdraw a coin after it has been introduced into the slot, the clip 12 will be pulled against the adjacent part of the bank wall and will thereby bind the coin in the slot and prevent its withdrawal.

The top 3 of the bank is preferably provided with a cover 14 of celluloid or the like, which adds to the appearance of the bank and also permits suitable names or inscriptions to be applied thereto. This celluloid cover or disk 14 is preferably secured to a metal disk 15 which is fitted firmly to the top 3.

In a similar manner the bottom 4 is provided with a celluloid disk 16, secured to a metal disk 17.

30 The interior member 5 may be formed of a blank 18, (Fig. 5) the ends of which are united with one another by dove tail joints 19.

In the bank shown in Figs. 6, 7 and 8, the

separate interior member 5 is dispensed with 35 and the lower member 20 has its upper end portion 21 reduced so as to fit or telescope into the lower end portion of the upper member 22. This lower member 20 is provided with one or more beads 23 which engage the groove 24 formed by the annular rim 25 punched in said member 22.

The spring coin engaging clip 26 is secured to the lower member 20 by rivets 27—27. In this form of bank the celluloid 45 disks are not arranged upon the top and bottom.

It will be understood that changes and modifications may be made without departing from the spirit of the invention.

50

What I claim is:

In a coin bank in combination, a container composed of two separably connected closed sections, each comprising substantially a half portion of the complete container, 55 means for normally frictionally maintaining the sections connected, a coin entrance slot in the side wall of one of said sections near the outer end thereof, an inner shell in one of the sections extending into the 60 slotted section, and means carried by said shell and extending across said slot for preventing extraction of the coin contents.

In witness whereof, I hereunto subscribe my name this 4th day of January, A. D. 65 1919.

ISIDOR J. KUSEL.
